INKING MECHANISM FOR ROTARY
PRINTING PRESSES

Howard M. Barber, Pawcatuck, Conn., assignor
to C. B. Cottrell & Sons Company, Westerly,
R. I., a corporation of Delaware

Application May 26, 1943, Serial No. 488,511

3 Claims. (Cl. 101—349)

In rotary printing presses, especially where quick drying inks and drying apparatuses are employed, it is necessary to run the press a sufficient time to bring the heating elements of the drying apparatus up to the required temperature to quickly and efficiently dry the impressions. During this heating-up period the ink supplied to the distribution should be cut off to prevent its loading up with an excessive amount of ink before the actual printing operation starts.

The object of my invention is to provide novel means for stopping and reestablishing the flow of ink from the ink supply to the distribution.

My invention comprises means for moving the ink transfer roller into and out of contact with its ink supply and distribution rollers, when desired, without affecting the drive for the ink supply roller or the initial adjustments of the ink transfer roller for parallelism, and while the press is running or at rest.

A practical embodiment of my invention is represented in the accompanying drawing in connection with a continuously driven ink supply or fountain roll.

Fig. 1 represents a detail end view partly in section, with the ink fountain bowl removed, of an ink distribution embodying my invention.

Fig. 2 represents a detail end view of the same with the ink transfer roller shown in its operative position in contact with its ink supply and distribution rollers.

Fig. 3 represents a detail section taken in the plane of the line III—III of Fig. 1, looking in the direction of the arrows, with the ink transfer roller shown in its inoperative position out of contact with its ink supply and distribution rollers.

Fig. 4 represents a detail cross section taken in the plane of the line IV—IV of Fig. 2, looking in the direction of the arrows.

Fig. 5 represents a detail section taken in the plane of the line V—V of Fig. 1, looking in the direction of the arrows.

The ink supply or fountain roller is denoted by 1 and it may be continuously driven, as through the usual gears 2 and 3, from a suitable drive not shown herein.

The ink transfer roller 4 is located between and in normal contact with its adjacent ink distribution roller 5 and the ink supply roller 1. The shaft 6 of the ink transfer roller 4 is journaled in end supports or sockets 7 slide longitudinally along shallow grooves 8 in brackets 9 secured by bolts 10 and their nuts 11 to the side frames 12. These bolts extend through lateral

elongated slots 13 in the brackets 9 and also through enlarged slots 14 in the end supports 7, where the bolts are provided with heads 15 which overlap the said end supports to retain them in the grooves 8.

The means for moving the ink transfer roller 4 into and out of its operative position may be constructed and arranged as follows: A hand operated rock shaft 16 is journaled in the said frames 12. A hand crank 17, located outside of one of the side frames, is provided for operating the said rock shaft. Stops 18 and 19 on the said side frame serve to limit the throw of the hand crank. This rock shaft 16 extends through longitudinally elongated slots 20 in the end supports 7 for the ink transfer roller 4 and also through longitudinally elongated slots 21 in the eccentric receiving blocks 22. Eccentrics 23 are provided on the rock shaft 16 for operating the end supports. In the present instance these eccentrics engage the opposite upper and lower parallel walls of transverse recesses 24 in the blocks 22. Upper and lower screws 25 and 26 extend through longitudinally elongated slots 27 and 28 in the end supports into threaded engagements with the eccentric receiving blocks 22 for securing them to said end supports.

The means which I have shown for initially and independently adjusting the ends of the ink transfer roller 4 both arcuately and radially to bring it into parallelism and proper normal contact with the ink supply and distribution rollers 1 and 5 is as follows: The brackets 9 are provided with pairs of adjusting screws 29 and 30 which engage the opposite sides of the bolts 10. By releasing the nuts 11 of said bolts 10 the screws 29 and 30 may be turned to individually adjust the brackets, their end supports, and the ink transfer roller 4 arcuately with respect to the said ink supply and distribution rollers.

The screws 25 and 26 which secure the eccentric receiving blocks 22 to the end supports are loosened when it is desired to adjust the blocks radially with respect to their end supports. To accomplish this radial adjustment of the end supports and thereby the ink transfer roller, screws 31 are journaled in lugs 32 projecting from the end supports, said screws being threaded into the eccentric receiving blocks 22.

In operation.—When it is desired to stop the flow of ink from the ink supply roll to the distribution the hand crank 17 is swung from its stop 18 to its stop 19 on the side frame. This movement will rock the shaft 16 and its eccentrics 23 and thus throw the transfer roller 4 out of contact

with its ink supply and distribution rollers. When it is desired to resume the inking of the distribution the hand crank may be returned to its original position, bringing the ink transfer roller into contact with its ink supply and distribution rollers.

It will be seen from the above description that the operation of the throw-off device will not disturb in the slightest degree the initial individual adjustment of the ink transfer roller with respect to its adjoining ink distribution and supply rollers.

It will also be seen that the transfer roller may be thrown into and out of its contact with the ink supply and distribution rollers whether the press is running or at rest.

It is evident that various changes may be resorted to in the construction, form and arrangement of the several parts without departing from the spirit and scope of my invention, and hence I do not intend to be limited to the particular embodiment herein shown and described, but what I claim is:

1. In an inking mechanism for rotary printing presses, ink supply, transfer and distribution rollers, side frames, a hand shaft journaled therein, brackets secured to the side frames, end supports for the transfer roller, longitudinally slidable in said brackets and slidably fulcrumed on said hand shaft, blocks adjustably secured to the end supports and having transverse recesses with parallel upper and lower walls, and eccentrics on the hand shaft engaging the upper and lower walls whereby the end supports and thereby the transfer roller is moved into and out of contact with the supply and distribution rollers by the rocking movement of the hand shaft.

2. In an inking mechanism for rotary printing presses, ink supply, transfer and distribution rollers, side frames, a hand shaft journaled therein,

brackets secured to the side frames, end supports for the transfer roller, longitudinally slidable in said brackets and slidably fulcrumed on said hand shaft, blocks adjustably secured to the end supports and having transverse recesses with parallel upper and lower walls, eccentrics on the hand shaft engaging the upper and lower walls whereby the end supports and thereby the transfer roller is moved into and out of contact with the supply and distribution rollers by the rocking movement of the hand shaft, means for initially adjusting the position of each of the end supports with respect to its bracket, and means for initially adjusting the position of each of the end supports with respect to its block, for bringing the transfer roller into parallelism with the supply and distribution rollers.

3. In an inking mechanism for rotary printing presses, ink supply, transfer and distribution rollers, side frames, a hand shaft journaled therein, brackets secured to the side frames, end supports for the transfer roller, longitudinally slidable in said brackets and slidably fulcrumed on said hand shaft, blocks adjustably secured to the end supports and having transverse recesses with parallel upper and lower walls, eccentrics on the hand shaft engaging the upper and lower walls whereby the end supports and thereby the transfer roller is moved into and out of contact with the supply and distribution rollers by the rocking movement of the hand shaft, means for initially arcuately adjusting the position of each of the end supports with respect to its bracket, and means for initially radially adjusting the position of each of the end supports with respect to its block, for bringing the transfer roller into parallelism with the supply and distribution rollers.

HOWARD M. BARBER.
